FIG. 1 is a perspective view of my design for a multiple-form furniture article, the article being illustrated in its assembled state in which it assumes the appearance of an oversized medicine ball composed of six identical segments whose edges are joined together by slide fasteners;

FIG. 2 illustrates the same article in its fully disassembled state in which the six segments are separated from each other;

FIG. 3 shows the article with two joined segments detached from the ball to define a chair and ottoman combination;

FIG. 4 illustrates the article with the ball divided to define two like hemispheres in side-by-side relation to

FIG. 5 shows the article with the ball divided to define two like hemispheres in perpendicular relation to create a backed chair.

I claim:

The ornamental design for a multiple-form furniture article, substantially as shown and described.
